[57] **CLAIM**

The ornamental design for a real estate sign system and carrier therefor, substantially as shown and described.

DESCRIPTION

FIG. 1 is a perspective view of a real estate sign system and carrier therefor, showing my new design;

FIG. 2 is an end elevational view thereof;

FIG. 3 is a front elevational view thereof;

FIG. 4 is a top plan view thereof;

FIG. 5 is a perspective view of a real estate sign system, including signs, sign standards and flags, and carrier therefor;

FIG. 6 is a perspective view of a sign standard;

FIG. 7 is a front elevational view thereof;

FIG. 8 is a side elevational view thereof;

FIG. 9 is a bottom plan view thereof;

FIG. 10 is a perspective view of a sign standard with sign and flag;

FIG. 11 is a perspective view of a sign standard with flags.

The broken line disclosure included in FIG. 10 is for illustrative purposes only and forms no part of the claimed design.
